US00D819047S

(12) **United States Design Patent** (10) Patent No.: **US D819,047 S**
 Bates et al. (45) Date of Patent: ** *May 29, 2018

(54) **DISPLAY SCREEN OR PORTION THEREOF WITH A GRAPHICAL USER INTERFACE**

(71) Applicant: **Dyson Technology Limited**, Wiltshire (GB)

(72) Inventors: **Adam James Bates**, Oxford (GB); **Andrew James Holden**, Gloucester (GB); **Rebecca Jayne Coleman**, Swindon (GB); **James Andrew Turner**, Swindon (GB)

(73) Assignee: **Dyson Technology Limited**, Malmesbury, Wiltshire (GB)

(*) Notice: This patent is subject to a terminal disclaimer.

(**) Term: **15 Years**

(21) Appl. No.: **29/579,369**

(22) Filed: **Sep. 29, 2016**

(30) **Foreign Application Priority Data**

Mar. 29, 1920 (EM) 003046606-0002

(51) LOC (11) Cl. **14-04**

(52) U.S. Cl. **D14/485**
USPC .....

(58) **Field of Classification Search**

USPC D14/485-95; D18/24-33; D19/6, 52;
